UNITED STATES PATENT OFFICE.

SAMUEL R. SHOUP, OF HOBOKEN, NEW JERSEY.

REGISTERING-HEAD.

1,096,762.

Specification of Letters Patent. Patented May 12, 1914.

Application filed November 28, 1911. Serial No. 662,898.

To all whom it may concern:

Be it known that I, SAMUEL R. SHOUP, a citizen of the United States of America, and residing at Hoboken, in the county of Hudson and State of New Jersey, have invented a certain new and useful Improvement in Registering-Heads, of which the following is a specification.

My invention relates to registering heads 10 and particularly to actuating gearing therefor, the object of my invention being to provide an actuating gear adapted to be thrown into and out of engagement with the numbering head and locking the same against 15 rotation in the out-of-gear position.

In the accompanying drawing, Figure 1 is a broken plan view showing my improved device applied to the registering head of a voting machine; Fig. 2 is a vertical section 20 showing the same applied to a pair of registering heads at a turnstile; Fig. 3 is a broken elevation indicated by the line 3—3, Fig. 1; Figs. 4 and 5 are side elevations of the master gears of Figs. 1 and 2 respectively; Fig. 25 6 is a plan view of certain of the registering head gears in position for assembly.

The numbering head illustrated is of the general type shown in my Patent, No. 853,127, on voting machines, and comprises 30 units, tens, and hundreds wheels, A, B, C, respectively, geared together through pinions 10 and 11, meshing on the one hand with teeth 12 on the rear of each wheel A and B, and on the other hand with gearing 13 on 35 the face of each wheel B and C.

In the embodiment of my invention shown in Fig. 1, the unit wheel is actuated from the voting spindle 14, through a pinion 15, meshing with the crown 16, of the master 40 gear 17, between which and the unit wheel A I arrange a sliding pinion 18. When the latter is in actuating position with relation to the unit wheel A, the long teeth 19 on this pinion mesh with the slots 20 in the master 45 gear 17, so that upon the rotation of the latter the sliding pinion 18 communicates its motion through these long teeth to the unit wheel, which thus registers the voter's choice. When the pinion 18 is moved out of gear 50 with the master gear 17, not only is the latter unable to effect the rotation of the unit wheel, but the latter is also locked against actuation from any source since the long teeth 19 are opposed by the uncut portions 55 21 of the periphery of the unit wheel A, so that in this position it is impossible to tam-

per with the count indicated by the registering head, since the latter is positively locked against rotation in either direction. In order to effect this shift of the pinion 18 into and out of gear with the master gear 17, any suitable mechanism may be employed. As a simple means for accomplishing this result I have shown a bracket 22 sliding upon the frame 23 of the registering head, and 60 provided with arms 24 lying on either side of the pinion 18. The bracket 22 is connected in any suitable manner to the rack 25 so that longitudinal motion which may be imparted to the latter from any suitable 65 portion of the mechanism of the machine is in turn transmitted to the pinion 18.

In a voting machine of this character, the voting spindle 14 carries differential gears 26, meshing with interlocking bars 27, as described in my patent above mentioned. This interlocking mechanism preferably limits the extent of oscillation of the spindle 14, so that the same can describe an arc of not more than 115° practically. If the interlocking bars 27 be thrown out of gear with the differential gears 26 on the spindle 14, the latter is then free to rotate through the full circle. This enables me to facilitate the resetting of the registering head for a new 75 count by arranging on the periphery of the master gear 17 opposite the actuating teeth 28 thereof, which are used during voting, a series of teeth 29 which when the interlocking bars are thrown out of gear with the 80 differential 26, mesh with the pinion 18 and thus expedite the return of the registering head to zero on the reverse rotation of the voting spindle 14. This series of teeth may 85 extend over an arc of practically 250° and in the usual case will comprise at least five teeth, so that upon the reverse rotation of the spindle, the count of the registering head is lowered 6 units per rotation instead of 90 only 1 to a rotation, as has heretofore been the 95 case.

This invention is obviously not limited in its utility to a voting machine, and may be advantageously employed in many different ways. I have shown as a single example of 105 another way in which this registering head may be used, a turnstile in which, for instance, it is desired to keep separate records of cash gate receipts and of transfers or deadheads. In this embodiment of my invention the turnstile 30 is provided with an 110 upwardly extending spindle 31 carrying

pinions 32 constantly in gear with the crowns of the master pinions 33 for two registering heads. The slideable pinions 18 are here connected by links 34 to the rock lever 5 35 actuated by the pull rod 36 controlled by the gate keeper. The movement of this rod 36 in one direction throws one of the pinions 18 into actuating position and the other out of actuating position, and vice versa on the 10 movement of the rod in the opposite direction. In view of the fact that the turnstile is constantly rotated in one direction and makes a quarter revolution for each person that passes the turnstile, four spaces 37 must 15 be provided on the face of the master pinion 33 which meshes with the sliding pinion 18, so as to actuate the latter upon each quarter revolution of the turnstile. Obviously the resetting of a counting head of this character 20 proceeds at a slower rate than that of the mechanism illustrated in Fig. 1, since the number of actuating teeth is less. Obviously also the movement of the slideable pinion out of gear with the master pinion has 25 the same effect of locking the unit wheel against rotation in the out-of-gear position so that it is impossible for the gate keeper to tamper with the count shown by the registering head.

30 I claim as my invention:—

1. A registering head comprising a geared unit wheel, a master gear and an interposed shiftable pinion and means in connection with the latter for operatively connecting said unit wheel and master gear and for locking said unit wheel when operatively disengaged from said master gear.

2. A registering head comprising a geared unit wheel, a master gear, and an interposed gearing operatively connecting said master gear and unit wheel in one position and locking said unit wheel against rotation in operatively disengaged position.

3. A registering head comprising an actuating pinion, a master gear constantly in

mesh therewith, a geared unit wheel and a pinion interposed between said unit wheel and master gear, said pinion being shiftable to out-of-gear position and serving in such position to lock the unit wheel against rotation. 50

4. A registering head comprising a master gear, a geared unit wheel and an interposed connecting pinion shiftable into and out of gear with said master gear and serving in 55 the out-of-gear position to lock said unit wheel against rotation, the gearing on said master gear being interrupted, for the purpose mentioned.

5. A registering mechanism comprising a 60 rotatable spindle, gear thereon, a master gear constantly in mesh therewith, a geared unit wheel, a shiftable pinion constantly in mesh therewith and means for shifting the pinion into operative engagement with the 65 master gear.

6. A registering mechanism comprising a master gear, a geared unit wheel and an interposed pinion constantly in gear with said unit wheel but shiftable into and out of gear 70 with said master gear.

7. A registering mechanism comprising units, tens and hundreds wheels, each counting wheel having an intermediate pinion gear to actuate the adjacent counting wheel 75 of higher denomination one tenth revolution for each complete revolution of the actuating wheel, an independent shiftable pinion gear constantly in mesh with the unit wheel, a master gear, means for rotating the master gear and independent means for shifting the pinion gear into and out of operative connection with the master gear. 80

In testimony whereof I have signed my name to this specification, in the presence of 85 two subscribing witnesses.

SAMUEL R. SHOUP.
